S. S. Thomas

Inventor

Attorney

UNITED STATES PATENT OFFICE.

HARRY WILLIAMS, OF DETROIT, MICHIGAN.

LOCK.

Application filed May 18, 1927. Serial No. 192,206.

My invention relates to a permutation lock shown in the accompanying drawings and more particularly described in the following specification and claims.

5 This invention is designed as an improvement on the lock shown and described in Patent No. 1,460,518 dated July 3rd, 1923, and since assigned to me.

10 Objection has been raised to this device as the chain may be forced or prized from its riveted connection with the lock barrel or from the plug to which the free end of the chain is secured.

15 The lock tumblers shown in the patent are cast or machined from heavy stock and greatly add to the manufacturing cost of the lock, due not only to the actual cost of production but also on account of the time required for assembling the same.

20 The primary object of the present invention therefore is to provide a simple, inexpensive and effective lock of the permutation type fitted with a staple, which may engage the links of a chain, shackle or other like device, the construction being such that the ends of the staple are concealed in the barrel of the lock, where they are secured by locking mechanism against unlawful tampering.

25 Another feature of the invention is to construct the staple with one of its legs relatively longer than the other, that the end of a longitudinally movable bolt may enter a socket in the long leg of the staple to secure it when locked, the other leg of the staple having a peripheral slot to receive an annular element carried by the bolt,—the construction being such that the interlocking portions are overlapped by other elements so they cannot be readily tampered with in an effort to release the staple.

30 A further object of the invention is to reduce the manufacturing cost by constructing the lock tumblers of sheet metal by suitable forming dies, the several tumblers being enclosed and nested together as a self-contained unit, whereby they may be simultaneously placed in position and thus reduce the time required for assembling the parts within the barrel of the lock.

35 Another feature of the invention consists in providing a yieldably supported suitable

40 audible click plate formed of sheet metal adapted to co-operate with a ball housed in the wall of the barrel, the click plate being formed with a central rectangular opening adapted to fit a rectangular portion of the longitudinally movable bolt supported in the wall of the lock barrel so that the click plate may rotate with the bolt, the cylindrical portion of the bolt extending through a central opening in the tumbler unit.

45 With the foregoing and other objects in view which will appear as the description proceeds, the invention further resides in the combination and arrangement of parts and in the details of construction hereinafter described and claimed, it being understood that changes may be made in the precise embodiment of the invention herein shown without departing from the spirit of the same.

50 In the drawings accompanying this specification:

55 Figure 1 is a side elevation of the lock showing the ends of the locking staple concealed within the barrel of the device, as when locked.

60 Figure 2 is a longitudinal sectional view through the lock—with parts broken away—showing the staple in locked position.

65 Figure 3 is a similar view showing the staple unlocked.

70 Figure 4 is a cross-sectional view taken on or about line 4—4 of Figure 2.

75 Figure 5 is an end elevation of the barrel of the lock with the cap and click plate removed to expose a ball acting in conjunction with the click plate to audibly indicate the progressive adjustment of the tumblers.

80 Figure 6 is a fragmentary longitudinal sectional view of the lock taken on or about line 6—6 of Figure 5 on an enlarged scale, showing several tumblers, nested together, the washers separating the tumblers,—also, the projecting tongue of the central longitudinally movable bolt extending through the aligned slots of the tumblers as when unlocked.

85 Figure 7 is a fragmentary longitudinal sectional view of the lock barrel taken on or about line 7—7 of Figure 6 showing the click plate ball in the socket of the barrel in which it is lodged;

Figure 8 is a cross-sectional view taken on or about line 8—8 of Figure 3.

Figure 9 is a perspective view of one portion of the enclosing case supporting the several tumblers and washers.

Figure 10 is a perspective view of one of the tumblers.

Figure 11 is a perspective view of a washer placed between the tumblers, provided with projecting ears extending between slotted openings in the enclosing case.

Figure 12 is a perspective view of a tumbler in which the first-named tumbler is nested.

15 Figure 13 is a perspective view of a frictional drag spring washer bent that the several tumblers may be yieldingly maintained against displacement.

Figure 14 shows another tumbler nested 20 with the preceding tumblers.

Figure 15 is a perspective view of an element cooperating with the elements shown in Figure 9, to enclose the several tumblers and washers.

25 Figure 16 is a perspective view of the elements shown in Figures 9 and 15 assembled to enclose the several tumblers and washers.

Figure 17 is a perspective view of the audible click plate showing its central rectangular opening to receive the rectangular portion of the central bolt.

Referring now to the letters of reference placed upon the drawings:

A denotes the lock barrel fitted at one end 35 with a cap B overlapping the wall of the barrel. C is a centrally disposed bolt provided with a projecting tongue C^a rigidly secured at one end to the cap B. D is a plunger secured to the bolt C provided with 40 annular flanges d, d extending in opposite directions from a central web d¹,—the tongue C^a reaching from the bolt into a radial slot formed in the annular flange of the plunger to insure its rigidity.

45 E is a bushing, secured in the barrel of the lock by a driving fit, having a central circular opening through which the bolt C is adapted to move. F denotes a staple, one leg of which is longer than the other extending 50 transversely through the wall of the lock barrel. F¹ is a pin projecting from the long leg of the staple, adapted to bear against the wall of the lock chamber to preclude its removal.

55 Extending transversely into the long leg of the staple is a bore f to receive the end of the bolt C, when the staple is pushed into the barrel of the lock, as when locked. The short leg of the staple is provided with 60 a peripheral slot f¹ to receive the annular flange d of the plunger D when the staple is in locked position as in Figure 2.

G denotes one-half of a sheet metal case adapted to enclose a number of tumblers and 65 washers in spaced relation. The element G

has a plurality of fingers g, g, the purpose of which will be hereafter explained.

H indicates the other element of the enclosing case with its rim indented to form lugs H¹ extending between the spaced fingers 70 g, g of the element G—see Figure 16—to prevent movement between the parts when assembled to enclose the tumblers,—the fingers g, g being bent to overlap the first named element to secure the parts together.

I represents one of a plurality of tumblers having a pair of upstanding lugs I^a spaced apart, adapted to be engaged by a tongue C^a, carried by the bolt C in effecting an adjustment of the other tumblers. The tumbler I is also provided with a radial slot I^b to receive the tongue C^a of the bolt when releasing the locking mechanism.

J denotes a washer, located adjacent to the tumbler I, provided with a plurality 85 of ears J^a projecting from its perimeter between the spaced fingers g, g of the case G to secure the washer against rotation.

K denotes a tumbler having an arc-shaped slot K¹ to receive the longitudinally bent lug J^a of the tumbler I. L is a washer located 90 between the tumbler K and the nested tumbler M. The washer L however is bent to form a hump L¹ to provide a frictional drag that the tumblers may not become accidentally displaced when adjusted.

The washer L has projecting lugs L², L² which extend between the fingers g, g of the case G. The tumbler M is also provided with an arc-shaped slot M¹ of relatively different length to receive the lug K^a of the tumbler K and is further provided with a radial slot M^b adapted to be brought into registration with the radial slots G^b of the element G; I^b of the element I; K^b of 105 the element K; and M^b of the element M that the tongue C^a of the bolt C may pass through the respective slots to effect the unlocking of the device.

N denotes an audible click plate provided 110 with a central rectangular slot N¹ that it may be mounted upon the flattened portion C^b of the bolt C for rotation therewith.

P is a ball fitted in a socket formed in the end of the lock barrel in line with the path 115 of the corrugations N^a of the click plate N.

Q denotes a helical spring surrounding the bolt C and bearing at one end against the click plate and at the other against the inner wall of the cap B. The radial corrugations 120 N^a on the click plate are spaced apart at N^b to provide a neutral or starting point from which point the operator may begin counting upon rotating the cap B for the purpose of adjusting the tumblers to release the locking mechanism.

To secure the case enclosing the tumblers against movement when assembled in the lock barrel, the fingers g, g of the case G project through openings a¹ in the end wall 130

of the lock barrel and are bent to overlap the wall at a^2 in the respective recesses a^3 —see Figures 5 and 6. a^4 are metallic plugs fitted in the recesses and overlapping and concealing the fingers g ; g —see Figure 6.

The end of the bolt C may be secured to the cap B in any desired manner,—as indicated in Figure 6 it is riveted to an indented portion of the cap that the end of the bolt 10 may be flush with the outer wall of the cap to which it is riveted.

B^a denotes a filling plug lodged in the indented portion of the cap between the slotted portion of the bolt that the surface may 15 be flush with the surrounding wall of the cap.

Having now indicated the several parts by reference letters, the construction and 20 operation of the device will be readily understood.

In describing the operation of the device it will be assumed that the bolt is in its unlocked position as indicated in Figure 3, the short leg of the staple F being withdrawn 25 from the lock barrel and free to swing.

To lock the device the staple is forced into the side of the lock barrel until the short leg contacts with the shank of the bolt C limiting its further movement. The cap B 30 is then forced toward the end of the barrel of the lock against the action of the spring Q , thereby pushing the end of the bolt C into the socket f , provided in the long leg of the staple to receive it.

Synchronously therewith, the projecting 35 flange d of the plunger D enters the peripheral groove f^1 formed in the short leg of the staple. The cap B is then rotated causing the radially projecting tongue C^a of the bolt 40 C to engage the upstanding lugs I^b of the tumbler I , thereby rotating the latter and through the co-operation of the lugs I^a extending into the arc-shaped slot in the tumbler K causing its rotation,—while the lug 45 K^a of the tumbler K extending into the arc-shaped slot M^1 of the tumbler M successively disarranges the several tumblers thereby locking the device.

When it is desired to unlock the same, the 50 tumblers are rotated through the manual operation of the cap B to bring the radial slots I^b of the tumbler I , K^b of the tumbler K , and M^b of the tumbler M into registration with the slot G^b of the cover G that the 55 projecting tongue C^a of the bolt C may pass through the slots of the several tumblers due to the outward thrust of the spring Q bearing against the wall of the cap B thereby releasing the locking mechanism.

The adjustment of the cap B necessary to 60 bring the slots into registration is determined through the rotation of the audible click plate in accordance with the arbitrary arrangement of the arc-shaped slots of the 65 tumblers, the starting point for the rotation

of the cap being determined by a spaced portion between the corrugations of the click plate,—the operator after “feeling out” this spaced portion on the click plate counts the successive clicks of the plate until the 70 proper number have been attained by each tumbler through forward and reverse movements of the cap corresponding with the number of tumblers employed. Upon bringing the slots of the several tumblers into 75 registration, the tongue C^a on the bolt C passes through the radial slots in the several tumblers due to the urge of the spring Q upon the cap B thereby releasing the staple and unlocking the device. 80

Having thus described my invention what I claim is:

1. In a device of the character described, a lock barrel; a manually rotatable cap fitted to one end of the lock barrel; a rotatable and longitudinally movable bolt secured to the cap having a projecting tongue; a staple extending through lateral openings into the lock barrel, one leg of said staple being longer than the other and provided with a 90 socket to receive the end of the longitudinally movable bolt; a plunger secured to said bolt having an annular flange adapted to enter a peripheral groove in the short leg of the staple synchronously with the entry 95 of the bolt in the socket in the long leg of the staple; a serrated click plate sleeved upon the bolt and adapted to rotate therewith and through which the bolt has a limited longitudinal movement; a ball supported 100 in the wall of the lock barrel over which the click plate travels to produce a series of audible sounds; a spring located between the click plate and the rotatable cap; and a plurality of co-ordinating tumblers sleeved upon the bolt adapted to co-operate for adjustment with reference to each other through the manual rotation of the cap, whereby the tumbler mechanism may be so positioned that the bolt may be released 105 from locking engagement with the staple or the tumblers rearranged to secure the bolt against the release of the staple. 110

2. In a device of the character described, a lock barrel; a manually rotatable cap fitted to one end of the lock barrel; a rotatable and longitudinally movable bolt secured to the cap having a projecting tongue; a staple extending through lateral openings into the lock barrel adapted to be engaged by the bolt; a serrated click plate sleeved upon the bolt and adapted to rotate therewith and through which the bolt has a limited longitudinal movement; a ball supported in the 120 wall of the lock barrel over which the click plate travels to produce a series of audible sounds; a spring located between the click plate and the rotatable cap; and a plurality of co-ordinating tumblers nested together within a case to form a unitary device 125 130

sleeved upon the bolt, said co-ordinating tumblers being adapted for actuation by the tongue of the bolt, whereby upon the manual rotation of the cap the tumbler mechanism may be so positioned that the bolt may be released from locking engagement with the staple or the tumblers may be rearranged to secure the bolt against the release of the staple.

10 3. In a device of the character described, a lock barrel; a manually rotatable cap fitted to one end of the lock barrel; a rotatable longitudinally movable bolt secured to the cap, said bolt provided with a projecting tongue; a staple extending through lateral openings in the lock barrel adapted to be engaged by the bolt; a plurality of co-ordinating tumblers adapted to be actuated through the tongue of the bolt, said tumblers being nested together within a divided case, one portion of which is provided with fingers adapted to overlap the other portion of the case to secure the parts together and with other projecting fingers extending into a plurality of recesses in the wall of the lock barrel to secure the case therein; and means for determining an arbitrary pre-determined adjustment of the tumbler mechanism upon the manual rotation of the cap, whereby the bolt may be released from locking engagement with the staple or the tumblers may be rearranged to secure the bolt against the release of the staple.

4. In a device of the character described, a lock barrel; a manually rotatable cap fitted to one end of the lock barrel; a rotatable longitudinally movable bolt secured to the cap, said bolt provided with a projecting tongue; a staple extending through lateral openings in the lock barrel adapted to be engaged by the bolt; a unitary element comprising a plurality of co-ordinating tumblers adapted to be actuated through the tongue of the bolt, said tumblers being nested together within a divided case, one portion of

which is provided with fingers adapted to overlap the other portion of the case to secure the parts together and with other projecting fingers extending into a plurality of recesses in the wall of the lock barrel to secure the case therein; plugs fitted to said recesses and overlapping and concealing the ends of the fingers; sheet metal washers separating the respective tumblers, one of said tumblers being bent to provide a frictional drag between the several parts, to prevent the accidental disarrangement of the tumblers when adjusted; and means for determining an arbitrary pre-determined adjustment of the tumbler mechanism upon the manual rotation of the cap, whereby the bolt may be released from locking engagement with the staple or the tumblers may be rearranged to secure the bolt against the release of the staple.

5. In a device of the character described, a lock barrel; a manually rotatable cap fitted to one end of the lock barrel; a rotatable longitudinally movable bolt secured to the cap and provided with a projecting tongue; a bushing supported in said lock barrel through which the bolt extends; a staple extending through lateral openings in the lock barrel adapted to be engaged by the bolt; abutting means carried by the long leg of said staple to prevent withdrawal from the lock barrel; a plurality of co-ordinating sheet metal tumblers nested together adapted to be actuated through the tongue of the bolt; and means for audibly determining an arbitrary pre-determined adjustment of the tumbler mechanism upon the manual rotation of the cap, whereby the bolt may be released from locking engagement with the staple or that the tumblers may be rearranged to secure the bolt against release of the staple.

In testimony whereof, I sign this specification.

HARRY WILLIAMS.
